(57) **CLAIM**

I claim the ornamental design for an animal feeder, as shown and described.

DESCRIPTION

FIG. 1 is a perspective view of an animal feeder showing my new design.

FIG. 2 is an exploded view thereof.

FIG. 3 is a top plan view thereof.

FIG. 4 is a side elevational view taken from the right rear side which is a mirror image of the left front side.

FIG. 5 is a side elevational view taken from the left rear side which is a mirror image of the right front side.

FIG. 6 is a side elevational view thereof taken from the right rear showing the cradle separately for clarity of disclosure; FIG. 7 is a side elevational view thereof taken from the left rear showing the cradle separately for clarity of disclosure; FIG. 8 is a cross-sectional view taken along line 8—8 in FIG. 1; and,

FIG. 9 is a perspective view of a second embodiment of an animal feeder showing my new design.
